DETACHABLE HEEL LIFT

Esther E. R. Swanson, Milwaukee, Wis.

Application November 14, 1935, Serial No. 49,825

5 Claims. (Cl. 36—36)

This invention relates to heel lifts and particularly to heel lifts of women's low shoes or slippers.

The general object of the invention is the provision of a heel lift so constructed that when worn, it may be readily detached and a new heel lift placed upon the lower end of the shoe heel and in this connection to provide a heel lift which is so constructed that it may be readily put in place by anyone with the least possible trouble and without requiring any particular tools not found in any family and which, when applied, will remain firmly in place against any turning movement.

Another object is to provide a connection between the heel lift and the shoe comprising a screw, the screw having a portion of its length formed as a wood screw, the remainder of the length being formed as a metal screw with a relatively fine and low pitched thread, this screw after it is forced into the heel of a shoe, remaining therein, the lift itself being provided with a metallic plate having screw threads engaging the metal screw threads on the screw embedded in the heel.

A further object is to provide means, sold with the heel lift, whereby the screw may be readily turned into the heel initially and which will prevent a pair of pliers being used in an attempt to force the screw into the body of the heel and which will prevent the user from hammering the screw into place.

A further object is to provide a device of this character which will not mar the appearance of the shoe in any way and which will permit the ready detachment of worn heels at any time and the interchange of heels from a right hand shoe to a left hand shoe, for instance, so as to permit the even wearing down of the heels.

Other objects will appear in the course of the following description.

My invention is illustrated in the accompanying drawing wherein:

Figure 1 is a perspective view of a heel having my improved lift thereon;

Figure 2 is a vertical sectional view through the heel shown in Figure 1;

Figure 3 is a perspective view of the metallic plate which is embedded in the heel before the tongues are bent upward;

Figure 4 is a perspective view of a slightly modified form in which the plate is inserted within a recess formed in the lower face of the heel;

Figure 5 is a perspective view of the cap for initially attaching the shank 11 to the heel;

Figure 6 is a perspective view of the heel before the lift has been applied thereto.

Referring to this drawing, 10 designates a shank of metal, one end of which is formed to provide a relatively long pointed wood screw 11. The opposite end is formed to provide a relatively short screw threaded portion 12, the screw threads of which are low in pitch and relatively fine. Between these two portions 11 and 12, the shank 10 is unscrew-threaded, as at 13.

In order to provide means whereby this screw may be driven into the heel of a shoe, I design to sell with the screw itself a cap 14. This cap has an interior bore the same in diameter as the portion 12 of the shank 10, this interior bore being screw threaded. The cap may be many-sided in cross-section and is preferably provided at one end with a nick 15. The bore 16 of the cap has the same length as the screw threaded portion 12, so that when the cap is turned onto the portion 12, the inner end of the cap will bear against the end of the portion 12. When this cap is turned fully home on the screw, it is obvious that a screw driver may be used in the nick 15 to initially start the screw into the wood of the heel and after the screw is started, the pliers or a wrench may be used for turning the many-sided cap 14 in a direction to cause the further penetration of the shank 10 until the screw 11 has been forced its full length into the heel of the shoe with the portion 13 embedded in the heel. After the shank has been embedded in the heel, of course, the cap 14 is turned off, and its usefulness is over except for the fact that it may be used thereafter for fixing other screws in other heels.

The lift 17 is preferably made of rubber as is usual in the final lift of a heel and embedded within this rubber is a metallic plate 18. This plate has the shape of the lower end of the heel and is of such dimensions that the plate is less in area than the cross-section of the lift. In other words, the plate 18 has the shape of a semi-oval. Projecting from the straight edge of the plate at the middle thereof is a tongue 19 which is integral with the plate and which is formed with one or more perforations 20. Projecting from the straight edge of the plate on each side of the tongue 19 are the relatively short and relatively narrow tongues 21. The center of the plate 18 is formed to provide a central portion 22 which is interiorly screw threaded to engage with the threads of the screw threaded portion 12 of the shank 10. This central portion 22 is preferably thickened and constitutes in effect a nut 55

which is rigidly connected with and forms part of the plate 18.

The lift with the plate 18 embedded therein and the tongues 19 and 21 projecting therefrom is sold as one unit and with this heel lift, there is also sold, as part of the unit, the shank 10. The plate 18 is smaller than the lift 17 itself so that this lift may be cut down if necessary, to fit the heel in case the customer has bought a heel lift which is too large for the particular heel to be fitted with the lift.

In the use of this device, the shank 10 is screwed into the body of the heel A, as previously described and as shown in Figure 6 by means of the cap 14. The cap 14 is then removed and the lift 17 is screwed in place. There is an opening 23 in this lift which coincides with the opening in the central portion 22 and the screw threaded portion 12 of the shank is just long enough to permit this lift to be screwed home and tightly fit against the lower end of the heel A. After the lift has been screwed home, the tongue 19 is forced up against the breast of the heel and nailed thereto by one or more brads passing through the openings 20. These brads will be sold with the heel unit. The tongues 21 are then bent up against the inner face or breast of the heel. If desired, the tongue 19 may first be bent up and then a piece of leather may be glued over the tongue 19 to conceal it and then the brad driven through this covering and through one or more of the openings 20. On the other hand, all of the tongues 19 and 21 may be bent down and covered by a strip so as to entirely conceal these parts. Obviously, this will be a matter for the taste and convenience of the user.

It will be seen that this device permits the ready detachment of worn heel lifts and the ready replacement of these heel lifts by other heel lifts. It will also be seen that my construction prevents the heel lifts from turning around the center formed by the shank 10 and that the heel lifts will be held rigidly in place against any turning or twisting movement. When it is desired to remove the heel lift and replace it with a new heel lift, this may be readily accomplished by lifting up on the tongue 19 and pulling out the brads, then lifting up the tongues 21 until all the tongues are parallel with the heel lift and then rotating the heel lift to unscrew it from the shank. The shank, of course, is to be left in the heel and a new heel lift applied, as described. It will be noted that no tools have to be used in applying the screw or the heel lift of either except what is commonly found in any household, namely, a screw driver, and if desired, a pair of pliers or small wrench. Thus, anybody can apply the shank 10 to a heel and there is no necessity of a shoemaker to perform this operation. There will be no wear on the plate 18 nor on the nut-like center portion of the plate as these will be embedded within the heel lift itself. The construction permits not only the replacement of worn heels but permits heels on a pair of shoes to be transposed every so often to thus equalize the wear on these heels.

While I have described the plate 18 as being preferably embedded in a rubber lift, it will be understood that any composition may be used for forming this lift and that two sections of leather might be disposed one on each side of the plate 18 and thus embed the plate in the leather. I do not wish to be limited except as called for in the appended claims, to the embedding of the plate 18 within the lift, as the central underface

of the lift might be cut out and the plate 18 be disposed within this cut-out portion without the plate being actually embedded in the lift. It will be seen that the underface of the lift in the construction shown in the figures is imperforate so that no water will be forced up through a perforation and thus destroy or cause the deterioration of the screw shank or the coactive parts.

While I have before referred to this heel lift as being particularly applicable to women's shoes, it is to be understood that it is equally applicable to the heel lifts of men's shoes and children's shoes, or shoes of any style, the dimensions of the metallic plate and lift being, of course, changed to suit the style of shoe to which it is to be applied.

What is claimed is:—

1. As an article of manufacture, a heel lift attaching means including a plate formed for insertion within a heel lift and having a central thickened portion formed with a central threaded aperture, the plate having a tongue projecting from its inside edge, and a shank for holding the lift upon a heel, the shank having a wood screw for a portion of its length for engagement in a heel and having a machine thread on the remainder of its length and adapted to engage in the threaded aperture in the thickened portion of the plate.

2. As an article of manufacture, a heel lift including a plate embedded within the lift and having a central thickened threaded opening, the plate having three tongues projecting outward beyond the inside face of the lift, the middle tongue being longer than the lateral tongues and being apertured for the passage of a brad, the tongues being adapted to be bent up against the breast of a heel to which the lift is applied, the inside face of the lift having an aperture coinciding with the central aperture in the plate, and a shank for attaching the lift to the heel, the shank having one portion thereof formed of a wood screw and the remainder of the shank having a machine screw adapted to engage in the threaded opening in the center of said plate.

3. As an article of manufacture, a heel lift including a plate embedded within the lift and having a central thickened threaded opening, the plate having three tongues projecting outward beyond the inside face of the lift, the middle tongue being longer than the lateral tongues and being apertured for the passage of a brad, the tongues being adapted to be bent up against the breast of a heel to which the lift is applied, the inside face of the lift having an aperture coinciding with the central aperture in the plate, and a shank for attaching the lift to the heel, the shank having one portion thereof formed of a wood screw and the remainder of the shank having a machine screw adapted to engage in the threaded opening in the center of said plate, the lift having a cross-sectional area substantially greater than the area of the plate whereby the margin of the lift may be cut down to cause it to fit a heel.

4. As an article of manufacture, a shoe heel having a shank embedded therein, the shank having a portion projecting beyond the end face of the heel, this portion having a machine thread and a lift having a metallic plate embedded therein formed with a central thickened screw threaded portion engageable with the shank, the plate having three tongues projecting outward from the inside edge of the lift, the middle tongue being longer than the lateral tongues and being apertured, the tongues being bent upward against

the breast of the heel and the middle tongue being nailed to said breast.

5. As an article of manufacture, a heel lift including a plate embedded therein, the plate having a centrally disposed threaded aperture and the heel lift having a coincident opening on its inside face, the plate having a pliable tongue projecting outward beyond the inside face of the

lift, and a shank for holding the heel lift upon a heel, the shank having threads at its butt end adapted for engagement with the threaded aperture in the plate, the remainder of the shank having a pointed screw adapted for insertion in 5 a heel.

ESTHER E. R. SWANSON.
